Primary Examiner — Khawaja Anwar*Assistant Examiner* — Taylor O Mortorff(74) *Attorney, Agent, or Firm* — Mintz, Levin, Cohn, Ferris, Glovsky and Popeo, P.C. US(57) **CLAIM**

The ornamental design for a vacuum cleaner and vacuum nozzle, as shown and described.

DESCRIPTION

FIG. 1 is a front view of a vacuum nozzle, showing the claimed design;

FIG. 2 is a rear view thereof;

FIG. 3 is a top view thereof;

FIG. 4 is a bottom view thereof;

FIG. 5 is a left view thereof;

FIG. 6 is a right view thereof;

FIG. 7 is a perspective front, top right view thereof;

FIG. 8 is a perspective front, top left view thereof;

FIG. 9 is a perspective rear, top right view thereof; and,

FIG. 10 is a perspective rear, top left view thereof.

The broken lines in the drawings depict unclaimed subject matter that forms no part of the claimed design.
